GEORGE D. LEONARD, OF NEW YORK, N. Y.

Letters Patent No. 98,982, dated January 18, 1870.

IMPROVED SHOW-CASE FOR SILKS, COTTONS, &c.

The Schedule referred to in these Letters Patent and making part of the same.

To all whom it may concern:

Be it known that I, GEORGE D. LEONARD, of the city, county, and State of New York, have invented a new and useful Improvement in Apparatus for Displaying Silks, Cottons, and other articles, of which the following is a full, clear, and exact description, reference being had to the accompanying drawing, forming part of this specification, and in which—

Figure 1 represents a front view of my apparatus, as applied to the displaying of silk on spools, and

Figure 2, a longitudinal section of the same, taken as indicated by the line $\pi \pi$ in fig. 1.

My invention, although applicable to displaying various other articles, will here be described, by way of illustrating its action, in connection with the display of silk, or it may be cotton thread, or other like material, put upon spools.

Said apparatus may either be used as a portable device, for the display of samples by travelling agents, in soliciting orders, or be a fixture, or, rather, stationary appendage, in stores and other places, to facilitate the exposure either of samples, or the articles themselves on sale.

The invention consists in an apparatus made up of, or combining a case containing opposite end-rollers, an endless belt or belts, apron, or chain, carried and driven by said rollers, or by one of them, and swinging trays or spool-carriers, hung in brackets attached to the apron, belt, or chain, and so constructed or weighted as that in the travel of the apron, or its equivalent, in opposite directions and around the drums, the mouths of the trays are presented uppermost, which prevents the articles required to be displayed from falling out of the trays, in or during the travel of the apron, belt, or chain; and

The invention further includes the combination of a flexible slotted shutter with said case and mechanism therein, which secures display of the articles within the case.

Referring to the accompanying drawing—

A represents a case, made up of any suitable material, size, and shape, open in front.

Across this case, on its inside, are arranged end-drums or rollers B B, provided with trunnions or shafts, which project from either end of them, and turn in bearings made in the sides of the case, or in sliding-boxes made to fit therein, and adjustable by screws and nuts $a a$, which is the arrangement shown for the one drum, and the object of which is to tighten, as required, the endless belt or apron C, that is carried by the drums B B, and is set in motion by turning one of the drums, through a crank or handle, b, or otherwise.

Secured to this endless apron C, at or near its edges, are any number of outwardly-projecting brackets c c, arranged in opposite pairs, at equal or other distances apart.

In these brackets are hung, so as to be capable of freely swinging, by means of spindles or shafts d d, trough-like carriers or trays D D, of semicircular form in their transverse section, although they may be of rectangular or other shape, according to the description of the articles to be displayed, or position required to be given them in the trays. Thus, where the articles are spools of silk, for instance, the trays may be shaped either to hold the spools on end, or longitudinally; preferably, however, the latter, as represented in the drawing.

Attached to the spindles d d are weights e e, for preserving the trays D D in a horizontal position, with their mouths uppermost, when working the apron C, and as they pass around the rollers B B, whereby the articles carried by the trays are prevented from falling out of the latter, their proper exposure is secured.

The trays D D should only be of such a depth as that they will expose a large portion of each spool E lying therein.

Said spools have wound upon them various grades and colors of silk or other material.

From this description it will be seen that by turning the handle b, the spools are displayed in succession, or as required, and in a straight line or plane, as contradistinguished from a circular travel of them, that occupies much room, and gives but a limited exposure, and is defective as regards comparing shades; said spools E being displayed in succession, or as required, accordingly as the several trays containing them are brought in front of the case, and to any desired position thereof.

F is a flexible slotted or other suitable curtain-like shutter, passed over end-pulleys on the upper roller-trunnions, and having a weight, g, attached to its rear end, for taking up slack of the shutter, and to facilitate its working, in drawing it up or down, so as to more or less uncover the open front of the case A, or to entirely close the same, for protection of the articles in the trays from dust and light.

This shutter-arrangement or construction is specially applicable to a vertical position of the case A. When the case is designed to occupy a horizontal position, as, for instance, to lie on a counter, then, sliding, hinged, or other suitable doors may be substituted for the flexible shutter F.

What is here claimed, and desired to be secured by Letters Patent, is—

The arrangement and combination of the endless belt C, brackets c, and weighted swinging trays D, with the case A, rollers B, and flexible shutters F, substantially as shown and described.

GEO. D. LEONARD.
